JACKETED DISCHARGE LAMP

Thomas J. Kreps, South Euclid, Ohio, assignor to General Electric Company, a corporation of New York

Filed Mar. 16, 1966, Ser. No. 1,499

Term of patent 14 years

(Cl. D26—8)

FIG. 1.

FIG. 2.

FIG. 1 is a front perspective view of a jacketed discharge lamp showing my new design;

FIG. 2 is a top plan view thereof.

The dominant features of my new design reside in the portions shown in solid lines.

I claim:

The ornamental design for a jacketed discharge lamp, as shown and described.
